THERMALLY INSULATED WALL
STRUCTURE

Joseph M. Le Grand, Heathsville, Va.

Application July 14, 1934, Serial No. 735,146

23 Claims. (Cl. 72—16)

My invention relates to wall structure for buildings and enclosures, such, for example, as homes, office buildings, vaults, storage chambers, and the like; and it has to do more particularly with insulated walls for structures of the foregoing character.

One of the objects of the invention is to provide an improved thermally insulated wall structure which is of simple construction, is inexpensive to construct, and which is highly efficient in minimizing the transfer of heat by radiation, convection and conduction.

Another object is to provide a metallic wall unit which thermally insulates the wall and also receives and supports plaster or other wall-surface-finishing materials.

A further object is to provide an insulating unit of the foregoing character which may be readily and quickly applied to the wall structure and which may be matched with similar units to build up and complete one or a plurality of wall surfaces.

Still another object is to provide an all-metal unit of the foregoing character which includes one or more metallic sheets of sufficient stiffness and thickness to withstand preformed shape and which are formed of a material possessing relatively low reflective characteristics when exposed to radiation of wave lengths within the visible portion of the electromagnetic spectrum and relatively high reflective characteristics when exposed to radiation of longer wave lengths than the visible portion of the electromagnetic spectrum.

A more specific object is to provide an all-metal wall-forming unit which includes a wire mesh surface adapted to receive and support plaster or other wall-surface-finishing materials and to which there is fixedly attached, in spaced relation, one or more metallic sheets adapted to be disposed within the wall space defined in part by the wire mesh surface of the unit when the unit is fixed in place.

An additional object is to provide a thermally insulating wall unit which may be readily shipped and stored, which may be stocked in standardized sizes for sale and which, if necessary, may be readily and easily trimmed for re-sizing and matching by the user so as to fit irregularly sized and shaped wall surfaces.

Other objects are to provide a thermally insulated wall structure which is substantially free from condensation and the ill effects thereof; to provide a fireproof wall structure; to provide warp-proof wall surfaces; to provide wall struc-

ture which is strong and durable and which will afford near maximum thermal insulation for practically the life of the structure insulated; to provide an insulated wall structure which will reduce the cost of heating the interior of the enclosure formed thereby, and which will aid in the maintenance of a more nearly uniform temperature within such enclosure; and to provide a wall structure wherein the transfer of air therethrough by infiltration is reduced to the minimum.

Other objects and advantages will become obvious as this description progresses and by reference to the drawings, wherein,—

Figure 1 is an elevational plan view of one form of wall structure embodying this invention, certain of the parts of such structure being shown cut away to more clearly illustrate the relationship of the several parts thereof;

Fig. 2 is a section taken substantially on line 2—2 of Figs. 1 and 3;

Fig. 3 is a section taken substantially on line 3—3 of Fig. 2;

Fig. 4 is a view similar to Fig. 2 but showing another form of structure embodying the invention, which figure is taken substantially on line 4—4 of Fig. 5; and

Fig. 5 is a section taken substantially on line 5—5 of Fig. 4.

In the drawings, the invention is illustrated as applied to a wall structure such as may be employed in various forms of building structures; however, it is to be understood that this invention is applicable to any form of wall structure in connection with which similar conditions of use are to be met. The illustrated wall structure is particularly adapted for outer walls but, as in the case of an enclosure like a house or office building, structure embodying this invention may equally well serve for all the inner walls, including the ceilings and floors.

Referring particularly to the drawings, the wall structure shown includes the ordinary vertical stud members 10 spaced apart in a conventional manner and supporting at the outer sides thereof the usual boxing or outer covering 11 which, in turn, supports the finishing surface which may take the form of weather boarding 12 or any other suitable material. The studs 10 are mounted upon the bottom sill plates 13 and they support, at their upper ends, the usual cap plates 14. The studs, sill plates and cap plates, together with the outer wall structure and the inner wall structure, which will be described more fully hereinafter, form a closed wall space 15, there being,

preferably, a plurality of such spaces in each wall to be insulated.

The wall structure further includes an inner wall 16 which embodies important features of this invention and which will now be described in detail. The wall 16 takes the form of a plurality of metallic units each, preferably, of a size to extend throughout the length and width of one of the wall spaces 15. This unit includes a sheet 10 of wire mesh 17 which is, preferably, of sufficient length and width to overlap the inner edge surfaces of the studs 10 and the cap and seal plates 14 for securement thereto by staples 18.

The wire mesh sheet 17 supports within the space 15 an imperforate metallic sheet 19 which is of substantially the same dimensions as the space 15 so that its several edges fit snugly against the adjacent surfaces of the studs 10 and the sill and cap plates 13, 14. The metallic sheet 19 is fixedly secured to the wire mesh sheet 17 in substantially parallel relation with respect thereto as follows: Spaced vertical strands 20 of the wire mesh sheet are each provided with a plurality of spaced, inwardly extending, integral loops 21 which are spot-welded, or otherwise secured, to the adjacent face of the metallic sheet 19. The length of the supporting loops 21 may vary, depending upon the desired spacing of the sheet 19.

It will be seen that the inner wall unit 17-19 is of a character which may be readily and quickly installed. A plurality of these units, one for each of the spaces 15, may be employed to complete an entire wall surface, and where irregularities occur in the shape and size of the spaces 15, these units may be readily trimmed and matched to provide a uniform surface.

The wire mesh sheet 17 of the foregoing unit serves as a metal lath structure and it is adapted to receive a plaster body or covering 22 for finishing the inner wall surface. It is to be understood, however, if desired any other suitable form of wall finishing material which is secureable to the wire mesh sheet 17 may be substituted for the plaster without departing from this invention.

When the plaster 22 is applied to the outer surface of the wire mesh sheet 17, it naturally flows through the wire mesh openings 23 and covers the inner, as well as the outer side, of the wire mesh sheet so that, as the plaster dries and sets, it becomes securely bonded to the wire mesh sheet 17 in a manner which will be well understood. The metallic sheet supporting loops 21 are of sufficient length that, when the plaster 22 is applied, a space 24 is provided between the inner surface of the plaster 22 and the adjacent face of the metallic sheet 19.

As more fully explained in Letters Patent No. 1,910,703, granted to me on May 23rd, 1933, a large part of the total heat which is normally transmitted through a wall structure is by radiation transmission. I have found that the transfer of heat by radiation may be practically reduced to the minimum by the use of metallic sheets formed of a material which possesses relatively low reflective characteristics when exposed to radiation of wave lengths within the visible portion of the electro-magnetic spectrum and relatively high reflective characteristics when exposed to radiation of longer wave lengths than the visible portion of the electromagnetic spectrum, as more fully explained in my aforesaid patent. In using the expression "relatively low" and "relatively high" above, it is to be understood that this may mean low and high relative to each other, or low and high relative to material

such as aluminum or other bright surface materials or coatings. I have found that commercial black steel well serves this purpose, the sheets of steel being of sufficient stiffness and thickness to retain preformed shape. Such a material possesses relatively low reflective efficiency when exposed to visible radiation and relatively high reflective efficiency when exposed to infra-red radiation as in the present case. The metallic sheet 19, therefore, is formed of a material possessing the foregoing characteristics and I, preferably, employ commercial black steel for the material of such sheet. Furthermore, for reasons more fully pointed out in my aforesaid patent, the metallic sheet 19 is located comparatively close to the inner wall plaster surface 22 so as to render the sheet more effective as an insulation agent as against the transfer of heat by not only radiation but also convection and conduction. By closely fitting the edges of the sheet 19 to the studs 10 and sill and cap plates 13 and 14, the space 24 between the sheet 19 and the plaster 22 is substantially sealed from the remainder of the space 15 thereby dividing the space 15 into variable-depth spaces substantially sealed apart from each other, thereby further guarding against the setting up of convection currents which would tend to increase convection transfer of heat.

If desired, a plurality of metallic sheets may be mounted in the space 15 for increased insulation effects, dependent upon the particular wall structure, its environment and conditions of use. Such an arrangement is illustrated in Figs. 4 and 5. This form is the same as that of the previous figures except that the metallic sheet 25, which corresponds to the sheet 19, supports an additional and spaced metallic sheet 26. More particularly, in this form a sheet of wire mesh 27, which is secured to the vertical studs 28 and the cap and sill plates 29 and 30 by suitable staple devices, is provided with loops 31 which are fixed to the metallic sheet 25 by spot-welding or the like. The metallic sheet 26 is mounted parallel with the sheet 25 and it is preferably formed of the same material and to the same shape as the sheet 25 so that it fits between the studs 28 and the cap and sill plates 29 and 30 in the same manner as sheet 25.

The sheet 26 is supported upon the sheet 25 by rivet-and-sleeve devices 32-33. Specifically, a sleeve 33 of a length equal to the distance that the sheets 25 and 26 are spaced apart is mounted between these sheets and rivets 32, passing through the sheets 25 and 26 and through the sleeves 33, secure these parts together so that the sheets are held fixedly in the position shown in Fig. 5. In this form, the wire mesh sheet 27 supports, in effect, both of the sheets 25, 26 and these several parts constitute a self-contained unit which may be as readily applied to the wall structure as in the case of the unit of the previous figures. This wall surface is completed by plaster 34 as in the previous form.

In both of the previously described forms, the metallic sheet or sheets, preferably, have their surfaces preformed so as to provide therein a plurality of angular and intersecting plane surfaces 35 (Figs. 2 and 3) and 35' (Figs. 4 and 5), ribs 36 (Figs. 2 and 3) and 36' (Figs. 4 and 5) being provided at the intersection of these plane surfaces as disclosed in my aforesaid patent. By thus preforming and ribbing the metallic sheets, increased insulation effects are obtained and the sheets are strengthened and arranged to avoid vibration.

It is believed that the operation and advantages of my invention will be well understood from the foregoing. It will be seen that the invention provides combined lath and insulation means of unitary form which may be readily and quickly applied to a wall structure, and which, together with a finishing surface such as plaster or the like, serves to complete and finish the wall surface. Such an arrangement is inexpensive to manufacture and gives to the user, at the minimum of cost, a substantially permanent wall structure which is highly efficient in minimizing the transfer of heat by radiation, convection and conduction. This materially reduces heating costs and enables the user to maintain within a closure, such for example as a home, a more nearly uniform temperature. The invention further provides structure which may be readily manufactured at a source and shipped and stored for general sales purposes. The units may be readily trimmed and matched so that both regular and irregular wall surfaces may be built up and completely finished in a minimum of time.

It will be understood that while I have shown and described only two forms of structure embodying the invention, other changes in details and arrangements of parts may be made without departing from the spirit and scope of the claims which follow. For example, among other things, a greater number of metallic sheets may be employed. In some instances the metallic sheets may be plain-surfaced instead of as shown. Separate members may be employed for securing the metallic sheet to the wire mesh sheet, in which case such members should be securely fastened to both the insulating sheet and to the wire mesh sheet by welding or otherwise.

I claim:

1. A wall-forming unit which includes a sheet of wire mesh adapted to receive plaster or other wall finishing material, a metallic sheet having a high heat-reflectivity surface and of sufficient thickness and stiffness to retain preformed shape, and means for fixedly connecting said sheets together in spaced and substantially parallel relation throughout, the spacing between said sheets being such that an air space is maintained between said sheets when a wall-finishing material is applied to said mesh sheet.

2. A wall-forming unit adapted to have a wall-finishing material applied thereto which includes a sheet of wire mesh, a sheet of commercial black steel, and means rigidly connecting said two sheets together in spaced and substantially parallel relation throughout so that they may be applied and removed as a self contained unit, the spacing of said sheets being such as to provide an insulating air space therebetween upon the application of a wall-finishing material to said mesh sheet.

3. A wall-forming unit which includes a sheet of wire mesh, a metallic sheet formed of a material possessing relatively low reflective characteristics when exposed to visible radiation and relatively high reflective characteristics when exposed to infra-red radiation, and means fixedly securing said sheets together in spaced and substantially paralleled relation throughout to provide an air space for insulation purposes and to which one face of said metallic sheet is constantly exposed, said sheets being adapted to be applied and removed as a self-contained wall-forming unit.

4. A wall-forming unit which includes a sheet of wire mesh, an imperforate metallic sheet

formed of a material of sufficient stiffness and thickness to withstand preformed shape, said sheet having a high heat-reflectivity surface formed into a plurality of angular and intersecting plane surfaces, and means interconnecting said two sheets so that they may be applied and removed as a single wall-forming unit and for holding said sheets in predetermined spaced and parallel relation throughout their facing surfaces.

5. A wall-forming unit which includes a sheet of wire mesh, a metallic sheet having a high heat-reflectivity surface, and supporting members formed from said mesh sheet fixedly secured to said metallic sheet for support of the latter by the mesh sheet as a unit, said supporting members fixing a predetermined spaced and parallel relationship between said sheets throughout their facing surfaces.

6. A wall-forming unit which includes a sheet of wire mesh, a metallic sheet formed of a material of sufficient stiffness and thickness to withstand preformed shape and having a high heat reflectivity surface, and loop members formed from certain of the strands of said mesh sheet fixedly secured to said metallic sheet for support of the latter by the mesh sheet as a unit, said loop members fixing a predetermined spaced and parallel relationship between said sheets throughout their facing surfaces.

7. A wall-forming unit which may be pre-formed and applied to and removed from the wall as a unit which includes a metallic lath member adapted to be secured to wall-supporting means, an imperforate metallic sheet having a high heat-reflectivity surface and mounted in spaced relation to said lath member, means by which said metallic sheet is supported by said lath member in spaced relation throughout the surface of said metallic sheet, said lath member having provision for bonded support of plaster or other wall finishing material.

8. Wall structure which comprises a sheet of plaster, or the like, material, a sheet of metallic material imbedded within said plaster for bonded support of the latter, an imperforate metallic sheet having a high heat-reflectivity surface and being of sufficient stiffness and thickness to withstand preformed shape disposed in spaced relation to said plaster, and means projecting from said first metallic sheet and fixedly secured to said imperforate metallic sheet for support of the latter to provide a closed air space between said plaster and metallic sheet.

9. A wall-forming unit which may be applied to and removed from a wall structure as a unit which includes a metallic lathing sheet, a metallic sheet of sufficient stiffness and thickness to retain preformed shape mounted in spaced relation to said lathing sheet, means readily securing said lathing and metallic sheets together, another metallic sheet similar to the first metallic sheet mounted in spaced relation to the latter, and means rigidly securing said two metallic sheets together, both said metallic sheets having a high heat-reflectivity surface.

10. A wall-forming unit which may be applied to and removed from a wall structure as a unit, which includes a metallic lathing sheet, a metallic sheet mounted in spaced relation to said lathing sheet, means readily securing said two sheets together, another metallic sheet similar to the first metallic sheet mounted in spaced relation to the latter, and means rigidly securing said two metallic sheets together, said metallic sheets being formed of a material of sufficient

- thickness and stiffness to withstand preformed shape and possessing relatively low reflective characteristics when exposed to visible radiation and relatively high reflective characteristics when exposed to infra-red radiation.
11. A wall-forming unit that may be applied to and removed from a wall structure as a unit which includes a metallic sheet having means adapted to support a wall finishing material, a group of metallic sheets of sufficient thickness and stiffness to retain preformed shape secured together in spaced and substantially parallel relation with respect to each other, and means securing said group of sheets to said first metallic sheet in spaced substantially parallel relation with respect to the latter, said group of metallic sheets having surfaces of high heat reflectivity.
12. A wall-forming unit that may be applied to and removed from a wall structure as a unit which includes a metallic sheet having means adapted to support a wall finishing material, a group of metallic sheets formed of commercial black steel, said group of sheets being secured together in spaced and substantially parallel relation with respect to each other, and metallic means projecting from said first sheet for securing said group of sheets to said first metallic sheet in spaced and substantially parallel relation with respect to the latter.
13. In structure of the class described, a pair of walls defining an air space to be insulated, one of said walls including a plaster-supporting member, a metallic sheet having a high heat-reflectivity surface and carried by said plaster-supporting member in spaced relation to the latter, and a plaster material carried by said plaster-supporting member in spaced relation throughout with respect to said metallic sheet.
14. In structure of the class described, a pair of walls defining an air space to be insulated, one of said walls including a wire mesh sheet, an imperforate metallic sheet having a high heat-reflectivity surface, means by which said metallic sheet is supported from said wire mesh sheet substantially parallel with and spaced from the latter, and a plaster material carried by said wire mesh sheet in spaced relation throughout with respect to said metallic sheet.
15. In structure of the class described, a pair of walls defining an air space to be insulated, one of said walls comprising a unitary structure including a wall-finishing element, a metallic supporting member to which said element is bonded, and a metallic sheet having a high heat-reflectivity surface and carried by said supporting member in spaced relation to and substantially parallel with the latter and said wall-finishing element and of such size and shape as to divide said space into a plurality of air spaces substantially sealed apart from each other.
16. In structure of the class described, a pair of walls defining a space to be insulated, one of said walls comprising a unitary structure including a wall-finishing element, a metallic supporting member to which said element is bonded, and a metallic sheet carried by said supporting member in spaced relation to and substantially parallel with the latter and of such size and shape as to divide said space into a plurality of air spaces substantially sealed apart from each other, said metallic sheet being of sufficient stiffness and thickness to withstand preformed shape and formed of a material possessing relatively low reflective characteristics when exposed to radia-
- tion of wave lengths falling within the visible portion of the electro-magnetic spectrum and relatively high reflective characteristics when exposed to radiation of longer wave lengths than the visible portion of the electromagnetic spectrum.
17. In structure of the class described, a pair of walls defining an air space to be insulated, one of said walls comprising a unitary structure including a wall-finishing element, a metallic supporting member to which said element is bonded, and a metallic sheet carried by said supporting member in spaced relation to and substantially parallel with the latter and said wall-finishing element and of such size and shape as to divide said space into a plurality of air spaces substantially sealed apart from each other, said metallic sheet being of sufficient stiffness and thickness to withstand preformed shape and having its surface divided into a plurality of angular and intersecting planes with rib members at the intersections of said planes, said surface having high heat-reflectivity.
18. In structure of the class described, the combination with an outer wall and supporting means therefor, of means forming an inner wall and defining an air space to be insulated which includes a supporting member, means securing said member to said supporting means, a metallic sheet having a high heat-reflectivity surface within said space in spaced relation to said supporting member, means connecting said supporting member and metallic sheet whereby the latter is supported by the former, and a wall-finishing element carried by said supporting member on the side of the latter opposite said metallic sheet and in spaced relation to said metallic sheet.
19. In structure of the class described, the combination with an outer wall and supporting means therefor, of means forming an inner wall and defining an air space to be insulated which includes a metallic supporting member, means securing said member to said supporting means, a metallic sheet having a high heat-reflectivity surface within said space in spaced relation to said supporting member, metallic means connecting said supporting member and metallic sheet whereby the latter is supported by the former, and a non-metallic wall-finishing element carried by said supporting member on the side of the latter opposite said metallic sheet and in spaced relation to said metallic sheet and sealing one side of the space between said metallic sheet and metallic supporting member.
20. In structure of the class described, means forming a closed air space of comparatively shallow depth, said means including a wall forming unit which comprises a metallic sheet having a high heat-reflectivity surface mounted in said space with its edges engaging the edges of said space to divide the latter into a plurality of air spaces substantially sealed apart from each other, a perforated sheet secured along one side of said space substantially parallel with said first sheet, means connecting said two sheets so that they may be applied and removed as a self-contained unit, and a wall-finishing covering mounted on said second sheet on its side opposite said first sheet and in spaced relation to said first sheet to close one side of the space between said two sheets.
21. In structure of the class described, means forming a closed space of comparatively shallow depth, said means including a wall forming unit

which comprises a metallic sheet formed of a material possessing relatively low reflective characteristics when exposed to visible radiation and relatively high reflective characteristics when exposed to infra-red radiation mounted in said space with its edges engaging the edges of said space to divide the latter into a plurality of air spaces substantially sealed apart from each other, another sheet secured along one side of said space substantially parallel with said first sheet, said sheets being so spaced apart that the space therebetween is of comparatively shallow depth, means connecting said two sheets together as a unit, and a wall-finishing covering mounted on said second sheet on its side opposite said first sheet.

22. In structure of the class described, means forming a space to be thermally insulated, said means including a wall unit which comprises a metallic lath member extending over one side of said space, a plurality of imperforate metallic sheets of sufficient thickness and stiffness to retain preformed shape mounted in said space in spaced relation with respect to each other and to said metallic lath member, said sheets being formed of a material possessing relatively low reflective characteristics when exposed to visible

radiation and relatively high reflective characteristics when exposed to infra-red radiation, means rigidly fastening said metallic sheets together and to said metallic lath member whereby said sheets and member may be applied to and removed from the wall structure as a unit, and a wall finishing material carried by said lath member.

23. In structure of the class described, means forming a space to be thermally insulated, said means including a wall unit which comprises a metallic lath member extending over one side of said space, a plurality of steel sheets having a high heat-reflectivity surface and of sufficient thickness and stiffness to retain preformed shape mounted in said space in spaced relation with respect to each other and to said metallic lath member, said steel sheets extending throughout said space to divide said space into a plurality of air spaces substantially sealed apart from each other, means rigidly fastening said steel sheets together and to said metallic lath member whereby said sheets and member may be applied to and removed from the wall structure as a unit, and a wall finishing material carried by said lath member.

JOSEPH M. LE GRAND.
